DOBBY MECHANISM

This invention relates to dobbies for weaving looms, used principally for operating the heald shafts of a loom, (but, as explained below, useful also for some other purposes), and in particular to the generic type of dobbi known principally as a "Leeming positive open-shed dobbi, or head-motion".

U.S. Pat. No. 3,115,899 which corresponds to British Pat. specification No. 904,322 describes an improved arrangement of Leeming-type dobbi which is capable of reliable operation in connection with wide and heavy looms such as are required for weaving paper-machine felts, wherein much greater loads and forces are involved than in an ordinary loom, and which is responsive to a pattern record set for risers and fallers, in place of the pattern record set for changes as is usual with the ordinary Leeming-type dobbi. Both purely mechanical and electromechanical converter mechanisms, which enable the pattern record to be set for risers and fallers instead of for changes, are described in the patent specification aforesaid.

According to the aforesaid U.S. patent, the cam levers are lifted by a mechanical relay and lowered by gravity but under the control of the relay, which relay is actuated by a rotary cam. By their vertical movement, either up or down, the cam-levers slide their respective segment-gears along the splined driving shaft, either into or out of the fixed planes of their associated crank-gears. During each revolution of the loom crankshaft, the said mechanical relay first lowers all the previously lifted cam-levers (thereby shifting the associated segment-gears out of the planes of their mating crank-gears), then pauses for a new selection to be made, after which the relay lifts the newly selected cam-levers (thereby shifting the segment gears into the planes of their mating crank-gears) and then retains them in that position while the gears turn in mesh, and change the positions of the heald shafts concerned. The necessity to lower all the previously lifted cam-levers prior to the new selection, even though some of them may be required to be lifted again for the next sequence, seriously restricts the crankshaft angles available for the up and down movements of the cam-levers, which operations, including the intervening pause for the new selection, must be completed within the angle during which the heald shafts dwell in their open-shed positions.

The object of the present invention is to provide improved means for actuating the said cam-levers, whereby their actual movement, either up or down (as the case may be) may occupy nearly the entire angle of dwell of the heald shafts, and, furthermore, whereby the cam-levers make no down movements other than those essential for the effective operation of the dobbi mechanism.

According to this invention, each cam-lever is independently lifted or lowered, (meanwhile swinging on its fulcrum-bar), by a double-acting slave cylinder powered by fluid pressure. The lower end of the cylinder is hinged on a through-bar supported in the dobbi frames, while the protruding end of the piston rod is hinged to the cam-lever, at a suitable distance from its fulcrum. The said cylinder is preferably provided with cushioning means at both ends of the piston's stroke, with internal stops against which the piston is retained by fluid pressure in either its extreme up or down position, until required to make a further stroke in the opposite direction.

According to another feature of the invention, the flow of pressure fluid to and from the said double-acting slave cylinder is controlled by a two-position valve provided with two solenoids. This valve is adapted to be shot over in one direction or the other when one solenoid, or the other, is momentarily energized, and after having been so shot over in either direction remain in that position indefinitely until the other solenoid is next momentarily energized, and so on.

According to another feature of the invention, the two solenoid coils of each valve are controlled by an electric pattern-switch responsive to the weaving pattern record in combination with an electric position-switch responsive to the position, either up or down, of the associated heald shaft, or equivalent moving part, of the dobbi mechanism. Each such pattern-switch and position switch is provided with double-pole chan-

geover contacts (or the equivalent) which are interconnected to produce the open-shedding sequence exactly as indicated by the pattern chain, or other form of record, set for risers and fallers.

According to a further feature of the invention, a timing switch actuated by the loom crankshaft, or equivalent shaft, controls the current supply to the whole of the paralleled electric control circuits, being arranged to complete the said circuits so as to render them operative for somewhat less than the angle of heald shaft dwell, and to interrupt the said circuits throughout rather more than the angle of change, during which latter angle the gears are actually turning in mesh. The hand-operated leveling lever, which lifts all the pattern-switch sensing levers not already raised by the pattern chain, may therefore be operated at any time in the crankshaft revolution without danger of damage or derangement, because any such operation of the leveling lever becomes effective only as and when the timing switch closes, by which time the gears have turned out of their changing angle into their dwelling angle.

In a modification of the invention, the pattern-switch and the position switch are each provided with single-pole changeover contacts (or the equivalent) which serve to energize an electric relay also provided with single-pole changeover contacts, (or the equivalent) the two switches, the timing switch, the relay and the said valve solenoids being interconnected to produce the desired open shedding sequence indicated by the pattern chain set for risers and fallers.

The invention will be described further, by way of example only, with reference to the accompanying drawings illustrating three embodiment thereof and in which:

FIG. 1 is a diagrammatic elevation of the mechanism for controlling the position of the cam lever of a dobbi of the Leeming type;

FIGS. 1a and 1b are front elevations of cam formations provided in opposed disposition in the cam lever;

FIG. 2 is a schematic representation of one form of relay and the operation thereof in positionally controlling the cam lever;

FIG. 3 is a view corresponding to that of FIG. 2 and shows an alternative form of relay; and

FIG. 4 is a view again corresponding to FIG. 2 and showing a still further form of relay.

Thus referring to the drawing and particularly to FIG. 1 thereof, a cam lever 11 whereby a segment gear 12 is slidable axially on a splined shaft 13 in conventional manner via a shifter 14 into or out of mesh with a crank gear 15 according to a pattern sequence is positionally controlled by a double-acting slave cylinder 16 mounted on a bar 17 secured in position on the loom framework (not shown).

The segment gear 12, and its constructional and operational relationship with the various parts of the dobbi mechanism in lifting or lowering the heald frames is well known in the art, and is described in great detail in the above-mentioned U.S. Pat. No. 3,115,899.

The present invention is concerned with the means whereby the cam lever 11 is lifted or lowered according to a change in the shedding requirements of the loom, thus to move the segment gear 12 axially of the splined shaft through the medium of the cam surfaces 18 on the lever 11 and the cooperating cam followers 19 on the shifter 14, such means comprising the double-acting slave cylinder 16 and the control arrangements thereof.

As illustrated the said slave cylinder is pivotally connected at one end to the through bar 17 by a pin 16a and has projecting from its opposite end a piston rod 16b the inner end of which is fixed to a piston and the outer end of which is pivotally connected to the cam lever 11 by a pin 11a. The cylinder 16 contains cushioning means 16c at both ends and stops 16d against which the piston is held by the fluid pressure at either extreme position, the cushioning means and stop means indicated at 16c and 16d in FIG. 2.

One control arrangement is shown in FIG. 2 and will be seen to comprise a two position valve 20 provided with two sole-

noids 21, 22, the solenoids 21, 22 being adapted, upon momentary energization, to set the valve 20 in one or other of two positions, such valve feeding pressure fluid to one side or other of the piston of the slave cylinder 16 according to its position.

The electrical circuit for the two solenoids includes an electric pattern switch PA responsive to the weaving pattern record, in combination with an electric position switch PO responsive to the position of the associated heald shafts as indicated by the jack levers, the said switches PA, PO each being provided with double-pole changeover contacts as indicated. A timing switch T is provided within the electrical circuit of the control arrangement whereby the change in valve setting is arranged to occur only at a predetermined time in the loom cycle.

It will be apparent from the control arrangement shown in FIG. 2 that either the change solenoid 21 or the no-change solenoid 22 will be energized according to the relationship between the requirement of the pattern switch PA and the setting of the position switch PO, and the slave cylinder 16 will be actuated or not, as appropriate, to change the position of the cam lever 11 to raise or lower the related jack lever 23, and thus the position of the related heald frame.

An alternative control arrangement is shown in FIG. 3 and again includes a two position valve 20' having two solenoids 21', 22', associated therewith, the said valve-feeding pressure fluid to the slave cylinder 16 as before. The electrical circuit for the solenoid differs from that as shown in FIG. 2 in that instead of the pattern switch and position switch PA and PO respectively having double-pole changeover contacts, single-pole changeover contacts are provided and a solenoid 24 sensitive to the relative positions of the pattern and position switches is included, which solenoid, according to its position, energizes the change or no change solenoids 21', 22' at each loom cycle. In the case of the control arrangement of FIG. 3 the timing switch T has two contacts A and B, contact A closing shortly before contact B thus to ensure that the solenoid 24 is operated in advance of the change or no-change solenoid as appropriate.

A still further alternative control arrangement is shown in FIG. 4, the electrical circuit differing from that of FIG. 2 in that the pattern switch PA has single-pole changeover contacts, whilst the position switch PO has double-pole changeover contacts but with such contacts interconnected in the manner illustrated. As with the arrangement of FIG. 2, so the arrangement shown in FIG. 4 has a single timing switch T, and the functioning of the arrangement is similar.

It is an important advantage of this invention that the timing diagrams of the dobby events may be arranged so as to be substantially symmetrical, thereby enabling the dobby to function correctly while the loom crank-shaft and the dobby driven therefrom are temporarily reversed.

While the improved mechanism is suitable for actuating vertical jack levers in the general manner described in U.S. Pat. No. 3,115,899, it is also particularly adapted for actuating horizontal jack levers, in which case it is preferred to construct the dobby in two parts, one of which is disposed at each end of the loom structure. The electric control enables the entire pattern chain and its driving arrangements to be located at one end of the loom from which electric signals are conveyed by simple circuitry to both parts of the mechanism.

As already mentioned, the dobby mechanism herein described is also useful for any other purpose where a member requires to be moved on a timed sequence between two limiting positions, with the advantage of remote control when necessary.

We claim:

1. In a Leeming-type dobby mechanism embodying pairs of segment and crank gears supported on spaced parallel shafts, said segment gears being movable laterally on their shafts into and out of engagement with their associated crank gears in ac-

cordance with the dictates of a pattern, and operable while in engagement with the crank gears to impart a half revolution at a time thereto, a cam lever astride each segment gear, said cam lever embodying cams operable by movement of the cam lever towards the crank gear to shift the segment gear laterally out of engagement with the crank gear and by movement away from the crank gear to shift the segment gear laterally into engagement with the crank gear; means supporting the cam lever for movement toward and from the crank gear comprising a fixed pivot at one end of the lever on which the lever is pivotally mounted, a reciprocal part at the other end of the lever to which the other end is pivotally connected and a motor operable to effect reciprocation of the reciprocal part in response to the dictates of the pattern.

15 2. Apparatus according to claim 1, wherein said motor comprises a pivotally supported cylinder and piston assembly, and said reciprocal part is rigidly connected at one end to the piston and pivotally connected at the other end to the lever.

3. Apparatus according to claim 2, comprising a two-piston 20 valve operable in one position to supply pressure fluid to one end of the cylinder and in the other position to supply fluid pressure to the other end of the cylinder, said valve in each of its positions being held in that position by the pressure fluid supplied thereto to effect such movement.

25 4. Apparatus according to claim 3, comprising two solenoids operable to effect movement of the two-position valve to effect movement of the valve from one end to the other and from the other end to the one, said valve being adapted to remain in its end position when shifted thereto by one solenoid 30 until actuated by the other solenoid.

5. Apparatus according to claim 4, wherein the solenoids are operated by the pattern comprising a position switch operable in series with the pattern switch to effect energization of the solenoids, said position switch being rendered 35 operative only if the last position of the cam lever associated therewith is such that the pattern dictates a change therefore.

6. Apparatus according to claim 4, comprising a two-position 40 solenoid operable switch for effecting operation of said valve and a position switch associated with each jack lever operable in serial with the pattern switch to energize the sole- 45 noid switch only if the last position of the cam lever associated therewith is such that the pattern dictates a change therefore.

7. Apparatus according to claim 5, wherein the segment 50 gear is constantly rotated and the crank is intermittently rotated through a predetermined angle of rotation of the segment gear and is idle for a predetermined angular rotation of the segment gear, a timing switch operable in series with the positioning and pattern switches through a period of somewhat greater duration than the period of rotation of the crank gear to disable the positioning and pattern switches and operable during a period of somewhat lesser duration than the period of dwell of the crank gear to actuate said switches.

8. Apparatus according to claim 5, wherein the pattern 55 switch, position switch and solenoids are interconnected so that when the pattern switch and position switch are positioned for effecting lateral movement of the segment gear a circuit will be completed to one of the solenoids operable to shift the two position valve to a position to supply pressure fluid to the lower end of the cylinder but if the position switch is not so positioned it will fail to complete the circuit to said solenoid.

9. Apparatus according to claim 8, wherein the position 60 switches and pattern switches are each double-acting switches.

10. Apparatus according to claim 8, wherein the pattern 65 switch is a single-pole single-acting switch and the position switch is a double-pole double-acting switch.

11. Apparatus according to claim 9, wherein the pattern 70 switch and position switch are single-pole single-acting switches and are operably connected by a solenoid operable double-pole double-acting switch in the solenoid circuit.
